be made in either direction longitudinally with respect to a strip of printing paper.

Still another object of the invention is to provide a new and improved adjusting mechanism for multiple impression printing wherein any one or all of the patterns may be subjected to adjustment while the press is in full operation, or, if preferred, when the press is at rest, and wherein the adjusting mechanism is not under load during normal operation of the device.

Still another object of the invention is to provide a new and improved adjusting mechanism for multiple impression printing machines wherein the registration of the impressions remains fixed once it is properly adjusted.

Still further among the objects of the invention is to provide a new and improved adjusting mechanism for multiple color, continuous printing machines which is positive in operation, delicate of adjustment and easily manipulated by hand to such an extent that the device can be operated by relatively inexperienced operators.

Included, also, among the objects of the invention is to provide an adjusting device of the type hereinabove identified which is adjustable to presses of any size, large or small, and which is likewise applicable to presses wherein a great many different impressions or different colors are to be printed upon a single continuous strip of printing paper by use of one or more impression cylinders.

The objects contemplate the provision of a mechanism, the parts of which are readily accessible for inspection, servicing and repair and which being operated with relatively light loads renders them capable of maintaining their perfection of adjustment for as long as the press to which they are applied continues to operate.

With these and other objects in view, the invention consists in the construction, arrangement and combination of the various parts of the device whereby the objects contemplated are attained, as hereinafter more fully set forth, pointed out in the claims and illustrated in the accompanying drawings, in which:

Figure 1 is an end elevational view of a printing press incorporating the print roll register mechanism.

Figure 2 is a transverse sectional view, foreshortened for the purpose of illustration, and taken on the line 2—2 of Figure 1.

Figure 3 is a vertical sectional view taken on the line 3—3 of Figure 1.

Figure 4 is a cross-sectional view of one of the impression rolls taken on the line 4—4 of Figure 3.

Figure 5 is a fragmentary longitudinal sectional view of one end of one of the impression rolls taken on the line 5—5 of Figure 4.

Figure 5A is a cross-sectional view taken on the line 5A—5A of Figure 5.

Figure 6 is a fragmentary transverse sectional view of one of the differential mechanisms taken on the line 6—6 of Figure 3.

Figure 7 is a fragmentary transverse sectional view taken on the line 7—7 of Figure 3.

The invention described herein constitutes a series of adjusting mechanisms which are incorporated into a printing press devoted to the purpose of printing a continuous pattern upon one side of a long strip of printing paper. Ordinarily, the particular type of printing press involved is one of relatively large dimensions which is particularly well adapted to printing upon paper measuring two or three feet or more in

width, although narrower widths of paper may be printed on the same machine.

An important feature of this type of press is that it may run continuously over long periods of time. It is suitable for printing such types of paper as wrapping paper, wall paper or any other type of paper usually handled in rolls upon which is to be printed either a multiple color design or a combination of other patterns or impressions which must be brought into correct register one with another.

In the present embodiment the printing press is one fitted to apply distinct and separate patterns upon a continuous strip of paper. These may be of different colors or may differ otherwise, depending upon the requirements of any particular job which might be run.

For practical operation the press chosen for the purpose of illustration is equipped with two separate impression rolls, upon each of which is operative a pair of plate cylinders. The invention involves, particularly, a means of changing the register of the impressions of the plate cylinders as they are reproduced upon the strip of paper. As previously noted, it is only the register in a longitudinal direction with respect to the strip of paper with which this invention is concerned.

Since there are illustrated four separate plate cylinders, it is necessary only that three of them be capable of adjustment inasmuch as no adjustment is needed for the initial impression. Consequently, one of the plate cylinders can be without provision for a longitudinal adjustment of any kind, and the remaining three may be provided with adjusting features bringing them into proper relationship with the first.

Another element which is important to consider in the design and operation of a multiple impression printing machine of the type herein described is speed of operation. In view of the costliness of large machines of this type, they can be made economically feasible only when run constantly at a relatively high rate of speed. To improve the economy of operation of this type of machine it is highly desirable that a set-up of plate cylinders for a given run may be made just as quickly as possible and also brought into correct register as quickly as possible. The last requirement is more advantageously accomplished when the adjustments can be made while the press is in operation and also wherein once made the adjustments remain fixed.

In the embodiment herein disclosed there is shown a multiple color printing press for printing four different colors or patterns on a single strip of paper, an end view of which appears in Figure 1. A supporting frame, generally indicated by the reference character 10, comprises the exterior of the machine. In dotted lines there is indicated an upper impression roll 11, a lower impression roll 12 and four print rolls or plate cylinders designated by the reference characters 1, 2, 3 and 4, and operable on the paper in the numerical sequence indicated.

The term "impression roll" as used herein means the entire roll including the sundry appurtenances and attachments mounted between end plates 13 and 14 of the frame. The impression rolls are those around which a strip 15 of paper is carried and against which the plate cylinders press the paper when ink is transferred from the plate cylinder surfaces to the paper.

The plate cylinder or print roll, as customarily referred to in the printing trade, may be de-

scribed as a cylindrical roll which bears on its surface a curved rubber or zinc plate or other type of plate upon which is a continuous arrangement of either patterns, figures or type, or a mixture of the same, depending upon the printing being engaged in. The application and arrangement of type or of plates having a pattern on the surface is a matter of conventional technique well-known in the printing art, and details will consequently be omitted here other than the disclosure of inking rolls 16 and 17 for each plate cylinder.

In normal operation the strip of paper 15 is passed over an idler roll 18 which presses it against the upper impression roll 11. While pressed against the roll the plate cylinder 1 makes a first impression which may be one color. The paper then passes downwardly into contact with the lower impression roll 12 and there receives the impression from the second plate cylinder 2. While still in contact with the lower impression roll the third cylinder 3 transfers its impression to the paper on the same surface as the impressions from cylinders 1 and 2. Then the strip of paper leaves the last mentioned impression paper and passes again into contact with the upper impression cylinder 11 and there receives the impression from the cylinder 4, after which the printed strip of paper leaves the machine in the approximate direction indicated by the reference character 15'.

This invention relates to a device for shifting the relative rotational position of the plate cylinders with respect to each other so that the impressions which they transfer to the surface of the paper 15 will be in register one with another. The means resorted to in the present disclosure consists of a mechanism commonly known as a differential controlled mechanism.

For driving the machine power is received from a drive shaft 20 from which it is transmitted directly to a counter-shaft 21. Both impression rolls are geared to the counter-shaft and driven thereby, and the impression rolls in turn are geared to the plate cylinders and ink rolls through a suitable system of gearing so that all of the plate cylinders and impression rolls operate in synchronism.

In the present arrangement plate cylinder 2 is made fixed in its adjustment with respect to impression roll 12. Therefore, the adjusting mechanism comprising a large part of the subject matter of the present invention is made operative upon only the plate cylinders 1, 3 and 4. In accordance with this selected design of the operating parts, power from the drive shaft 20 will, as illustrated in Figures 7 and 3, be transmitted to a casing 22 comprising in part discs 23 and 24, the first being keyed to the drive shaft 20 and the second being keyed to the counter-shaft 21.

Upon the counter-shaft 21 is keyed a collar 25 having integrally secured thereto a gear 26, shown in Figures 2, 3 and 7, which meshes with a gear 27 of relatively large diameter. The gear 27 is non-rotatably attached to a short sleeve 28 comprising a part of the impression roll 12. It will thus be apparent that the impression roll 12 and particularly the portion thereof in contact with the plate cylinder 2 has a positive drive connection from the counter-shaft.

Furthermore, as is particularly apparent in Figure 2, from the gear 27 there is a positive drive connection to a pinion 29 on the plate cylinder 2, and the pinion 29 meshes with a gear 30 on the ink roll 16 which, in this instance, is

grouped with the plate cylinder 2. The gear 30 in turn meshes with a gear 31 of the corresponding ink roll 17. It will, therefore, become apparent that the plate cylinder 2 and the impression roll 12 are both positively driven from the shaft 20 and have a fixed rotational arrangement one with respect to the other.

Since in the operation of the device it has been found most advantageous to adjust the register of the plate cylinder 1 with respect to the plate cylinder 2 before the register of the plate cylinders 3 and 4 are adjusted, a description of the precise mechanism for the adjustment of the plate cylinder 1 is felt will contribute more quickly to an understanding of the structural features involved in the adjusting mechanism. This involves an adjustment of the impression roll 11 which operates in conjunction with the plate cylinder 1.

In order to make possible an adjustment of that portion of the impression roll 11 which is in contact with the plate cylinder 1, some device may be provided for momentarily changing the speed of rotation of the impression roll 11 with respect to the speed of rotation of the impression cylinder 12 so as, in effect, to throw them slightly out of step with each other.

The invention herein disclosed relates to a mechanism which is capable of either momentarily increasing the speed or decreasing the speed of the impression roll 11 with respect to the impression roll 12 so that the alignment of the pattern printed upon the paper by the plate cylinder 1 may be advanced or retarded with respect to the impression transmitted by the plate cylinder 2 to bring about a perfect register of the two. This adjustment is accomplished in part by a differential mechanism contained largely within a differential housing 35 which cooperates with a gear train arrangement contained chiefly within the casing 22 previously referred to.

The mechanism for adjusting the register of both plate cylinders 3 and 4 is controlled by differential mechanisms of the same kind, and a description of one, as illustrated in detail in Figure 6, will suffice for all three so far as this portion of the adjustment is concerned.

The differential housing 35, as illustrated in Figure 3, is located centrally with respect to the sides of the end plate 30 and below the axis of the counter-shaft 21, as is apparent in Figure 2.

As represented in detail in Figure 6, the differential consists of the housing 35, a differential input shaft 36, a differential output shaft 37 and oppositely disposed bevel gears 38 and 39 mounted rotatably upon their respective axes within the rotatable housing which mesh with bevel gears 40 and 41, respectively, on the input shaft and the output shaft. A gear 42 on the input shaft 36 meshes with a pinion 43 which is keyed upon the counter-shaft 21. As a result of this arrangement, the counter-shaft is in positive driving relationship with the input shaft 36 of the differential, and this in turn drives the output shaft 37, normally at the same rate of speed as the input shaft.

By reference to Figure 1 it will be found that the output shaft 37 is located centerably and below the axis of the counter-shaft, itself located mid-way between the axis of the upper and lower impression rolls 11 and 12. Keyed to the output shaft is a sprocket 45 connected by a chain 46 to a smaller sprocket 47. The smaller sprocket is keyed to a central shaft 48 which

is rotatably mounted within the counter-shaft 21 as will be apparent in Figure 7. This means that the central shaft 48 is driven through the differential.

Figure 7 illustrates the gear train by means of which power traveling from the differential through the central shaft 48 is transmitted to and enabled to rotate the impression roll 11. As a result of this inter-connection of transmitting gears, it will become apparent that the speed of rotation of the impression cylinder 11 may be controlled to some extent and varied by manipulation of the differential just described. This change in speed, it will be appreciated, is only momentary but is sufficient to change the register of impressions from the plate cylinders a sufficient amount to register any circumferential patterns on the surfaces of the plate cylinders; that is to say, in this instance plate cylinders 1 and 2.

Specifically, the central shaft 48 is connected by means of a pair of bevel gears 49, 50 to a stub shaft 51 journaled upon brackets 52 and 53 which extend inwardly from the disc 24 in the casing 22. The stub shaft 51, as illustrated, is at right angles to the axis of the counter-shaft, and the axes of the two shafts 51 and 48 intersect.

Also located upon the stub shaft 51 is a worm wheel 54, and meshing with the worm wheel is a worm gear 55 which is, in turn, mounted upon a second stub shaft 56 extending through the disc 24 and eccentrically located relative to the center of the disc. At the other end of the stub shaft 56 is a gear 57 which meshes with an internal gear 58 located within a pocket 59 formed on the hollow interior surface of a geared or friction head 60.

The geared head 60 is provided, also, with an external gear, in this instance embodied in a gear or pinion 61 keyed to an extension 62 of the geared head 60. The pinion 61, as illustrated best in Figure 3, meshes with a large ring gear 63 which is an integral portion of the impression roll 11. Consequently, the impression roll 11 is connected by means of the gear train just described through the differential to the counter-shaft as contrasted with the positive gear drive from the counter-shaft through the gears 26 and 27 to the impression roll 12.

It is important to note in connection with the adjustment of the device that the differential housing 35 is provided with a flange 65 and that the flange is confined within a confining ring 66 bolted to the end plate 13 by means of bolts 67 in such a manner that the differential housing is free to rotate within the confining ring about its central axis. A sleeve 68 on the differential housing extends rotatably through the end plate 13 and has keyed to its outer end a worm gear 69. This construction is well illustrated in Figure 6.

In Figures 1 and 3 the worm gear 69 is shown meshing with a worm wheel 70, and the worm wheel in turn is mounted upon an adjusting rod 71 journaled in brackets 72 and 73 on the outside face of the end plate 13 and provided with a hand wheel 74. It is, therefore, apparent that by rotating the hand wheel 74 the differential housing 35 is also rotated a corresponding amount, and this rotation may be in either direction. Rotation of the differential housing 35 makes effective a change of speed of the output shaft 37 with respect to the input shaft 36; hence, any rotating mechanism controlled by the output shaft will experience a change in speed with

relation to the counter-shaft as a result of rotation of the differential housing. This means that since the impression roll 12 is positively driven by the counter-shaft and since the impression roll 11 is controlled through the differential, the impression roll 11 may be adjusted with respect to the impression roll 12.

The result of adjustment of the impression rolls with respect to each other is an adjustment of the register of impressions from the plate cylinders upon the paper. It will be clear, also, from the foregoing description that the impression rolls may be adjusted relative to each other while the machine is in operation or when the machine is static. The advance or retardation of speed of one with respect to the other is merely momentary and not of great magnitude.

A careful examination of the structure shown in Figure 7 will reveal that the geared head 60 is permitted to rotate with respect to the casing 22, and this is necessary in order to achieve the adjustment above described. The geared head 60 is shown bearing upon a friction ring 75 which is received within a recess 76 of the disc 24. For pressing the geared head into frictional engagement there are provided a series of coiled springs 77 retained by plugs 78 in suitable apertures 79 spaced circumferentially about the collar 25. These springs press in an axial direction against the geared head with a very considerable amount of force. The collar 25 is, in turn, fixed with relation to the counter-shaft 21.

Normally, the geared head and the casing 22 rotate together, but when the differential housing is rotated, the geared head is rotated slightly relative to the casing 22 against the force of friction which is constantly present. The plugs 78 provide an adjustment for the tension effect of the springs 77. Screws 80 make possible removal of the disc 24 from the casing 22.

For adjusting the plate cylinders 3 and 4 separate independent differential mechanisms are provided, both located adjacent the end plate 13 and grouped about the differential identified by the housing 35, as illustrated in Figures 1 and 2. As there shown, a differential identified with a housing 85 operates to adjust the register of plate cylinder 4, and a differential identified with a housing 86 is effective in adjusting the register of plate cylinder 3.

Since the mechanical principle involved in each of the last named instances is identical, the structure and operation of the differential identified with the housing 86 and its relationship to the plate cylinder 3 only will be described in detail. In this connection, the construction of the impression rolls is important, and for illustration the structure of the impression roll 12 is shown in detail in Figures 4, 5 and 5A.

In Figure 2, for example, there is shown a sprocket 87 on the counter-shaft 21 connected by means of a chain 88 to a sprocket 89 mounted upon the input shaft of the differential housing 86. In this instance, the input shaft will be precisely like the input shaft 36 previously described in connection with the differential housing 35 in Figure 6. The interior mechanism of the differential housing 86 is likewise similar to that of the differential housing 35 as is also the rotational mounting of the differential housing 86 within a ring 66'.

The differential housing 86 is provided with an output shaft 90 at the outside end of which is mounted a sprocket 91 connected to a sprocket

92 on a shaft 93 by means of a chain 94 in a one-to-one relation. The shaft 93 is centrally located within a hollow shaft 95 which, in turn, supports the left end of the impression roll 12 within the end plate 13. A corresponding shaft 96 supports the opposite or right-hand end of the impression roll 12 upon the end plate 14. The left end of the shaft 96 is visible in Figure 3, but the relationship to the remaining portions of the device is more clearly illustrated in Figures 4 and 5.

To make it possible for the adjusting mechanism to work, the impression roll 12 may be constructed in a manner similar in a very general way to the structure shown in Figure 7. This means that what has hereinbefore been designated as the impression roll 12 in fact consists of an impression cylinder 97 and a geared or friction head 98 held in frictional engagement with the impression cylinder. These and other working parts may be construed as constituting, when assembled as shown, the impression roll.

More specifically, the geared head comprises an internal-external gear having a hollow interior cavity or recess 99 and an annular edge 100 bearing frictionally against an annular ring 101 confined within a recess 102 situated on the face of a circular plate 103 attached by screws 104 to the left end of the impression cylinder.

In order to hold the geared head in frictional engagement, there is provided a collar 105 shown in considerable detail in Figures 5 and 5A. The collar has the shape of a split ring having a split 106 on one side which permits the collar to be clamped in non-rotational engagement with the hollow shaft 95 by means of a screw 107.

Within the collar are a series of four apertures 108, and in each aperture is a coiled spring 109 held in place by an adjustable plug 110. The springs, in turn, bear against a wear plate 111 on the left face of the geared head 98. Pressure of the springs, which is normally of considerable force, presses the geared head into snug frictional engagement with the circular plate 103 of the impression cylinder. It will be apparent that the geared head is free to rotate relative to the impression cylinder when sufficient force is exerted to overcome the frictional resistance between them.

The shaft 93 is provided with a bevel gear 112 meshing with another bevel gear 113 on a stub shaft 114. The stub shaft, in turn, is journaled upon brackets 115 and 116 forming parts of the circular plate 103. The axis of the stub shaft 114 is perpendicular to and intersects the axis of the shaft 93. Keyed to the stub shaft 114 is a wormwheel 117 shown meshing with a worm gear 118 in turn keyed to a stub shaft 119 eccentrically journaled within the circular plate 103. A pinion 120 keyed to the other end of the stub shaft 119 meshes with an internal gear 121 within the geared head 98. This gear train can readily be traced in Figures 4 and 5.

Now, by an examination of the lower right portion of Figure 2, it can be observed that an external gear 122 on the geared head 98 meshes with a pinion 123 of the plate cylinder 3. Consequently, there is a positive drive between the plate cylinder 3, the geared head 98 controlled by the differential 86. Gears 124 and 125 drive ink rolls 16 and 17 which cooperate with the plate cylinder 3. By way of illustration, an ink well or trough 126 is shown into which may dip the ink roll 17 in each instance.

For rotating the differential housing 86 there is provided a worm gear 130 meshing with a 75

worm wheel 131 in turn operated by a shaft 132 to which is connected a hand wheel 133. Rotation of the hand wheel 133 rotates the differential housing 86, and this rotation either advances or retards the relative rotational position of the geared head 98 with respect to the position of the impression cylinder 97 and also with respect to the relative rotational position of the impression roll 11 and its corresponding 10 geared head 134. This means that the impression transmitted from the plate cylinder 3 to the printed sheet of paper can be adjusted to register in the manner just described with relation to the impression from the plate cylinder 2, adjustment of which is fixed relative to the impression cylinder 97. The register also shifts for the same reason with respect to the impression transmitted by the plate cylinder 1 to the sheet of paper.

20 The same construction in general applies to the mechanism associated with the differential housing 85. In the last instance, a hand wheel 135 acting through a worm wheel 136 and worm gear 137 rotates the differential housing 85. This, in turn, through a sprocket 138 on a differential output shaft 139 rotates a shaft 140 by means of a chain 141 and sprocket 142, thereby causing rotation of the geared head 134 with respect to the impression portion of the plate roll 11 and with respect to all of the other rotating parts of the press.

For supporting in place the plate cylinders, mounting blocks 150 are used which carry the ends of shafts 151 upon which the plate cylinders may be adjusted in an endwise direction and thus set in proper register in a transverse direction. Locking wheels 153 fix the adjustment once it is made.

Other blocks 154 support the ink rolls, and the blocks 154 together with the blocks 150 at either end of the plate cylinder may be moved toward and away from the impression roll by manipulation of a hand wheel 155. The blocks, in turn, ride upon square shafts 156 located edgewise as illustrated in Figure 3. Details of the mountings and adjusting devices last described are set forth in detail in co-pending application, Serial No. 716,550, filed December 16, 1946, which matured into Patent 2,542,229 dated February 20, 1951.

50 In operation of the printing machine involving the present disclosure and the print roll register devices just described the sheet of paper 15 is fed into the machine around the roller 18 and against the impression roll 11 as previously noted. The sheet of paper passes over both impression rolls as illustrated in Figure 1. Normally, and likewise as heretofore described, the plate cylinder 2 is in fixed relationship to the impression roll 12 and the paper. All of the other plate cylinders are adjusted with relation to the plate cylinder 2. In a preferred sequence of adjustment the register of plate cylinder 1 is next adjusted, and this is accomplished by operation 55 of the hand wheel 74 which, through the differential mechanism described herein, adjusts the speed of rotation of the plate roll 11 and consequently the register of the plate cylinder 1 rotating in printing contact with the impression roll 11. The gears for driving the plate cylinder 1 and accompanying ink rolls are positively driven from the gear 63 at the right end of the plate roll 11 as viewed in Figure 3.

60 In the preferred order of adjustment the plate cylinder 3 is next set in register with the com-

11

combined register of plate cylinders 1 and 2. This is accomplished by manipulation of the hand wheel 133 which, in operating upon the differential identified with the differential housing 86, causes the geared head 98 to be adjusted relative to the other rotating parts. The plate cylinder 3, being positively driven by the geared head 98, takes its adjustment in this manner and causes the plate cylinder 3 to rotate relative to rotation of plate cylinders 1 and 2. This is sufficient to bring the impressions of plate cylinders 1, 2 and 3 into registration with each other.

Finally, by operation of hand wheel 135 registration of the plate cylinder 4 is effected by manipulation of the differential mechanism of the differential housing 85 in company with rotation of the geared head 134. This is possible because the plate cylinder 4 is positively driven by the geared head 134 and thereby is made to rotate relative to the other three plate cylinders.

What is further significant is the fact that when the press is in operation both impression rolls, all of the plate cylinders and all of the differential gearing, together with the geared heads, operate together and in synchrony. The housings only of differentials 35, 85 and 86 remain stationary. These move only when they are deliberately moved by manipulation of their respective hand wheels. Because of this interconnection, the adjustment of register of any one of the plate cylinders may be made at any time. Moreover, the adjustment is unlimited; that is to say, any one of the differential housings may be rotated throughout an arc of 360°, once, twice or as many times as need be, depending upon the gear ratios, the diameter of the plate cylinders and other factors.

The patterns, of course, will not exceed in extent the circumference of the plate cylinder. Since there is unlimited rotation of the differential housings, the adjustment may run clear through any pattern. Consequently, when the plate cylinders are set up initially, no more care need be taken than to place the plate cylinder in contact with the impression roll to a sufficient extent to make an even impression over the length of the roll. No attention at all need be given to the initial register of the plate cylinder in a longitudinal direction. This can all be taken care of by manipulation of the hand wheels and their respective differential mechanisms.

It is clear, also, that although the impression rolls may be made for the accommodation of strips of paper of relatively great width, narrower strips of paper may be printed in the press since it is necessary to do no more than limit the printing portions of the plate cylinders to a length no greater than that necessary to print paper of correspondingly narrow width.

In a press of the type described the printing may be run just as fast as is in keeping with the type of paper and ink selected. Great speeds can be attained without the rapid operation being detrimental to the printing of multiple colors upon the paper since once adjusted the register is held.

Because of ease in manipulating the adjustment, relatively few attendants are needed for presses of this kind which results in great economy in their operation. Because of it being possible to easily adjust the register, the printing paper results in very few seconds or poor runs and is consequently productive of an additional saving.

Moreover, because of the fact that the working

12

parts of the machine are exposed and easily accessible, the parts may be serviced with particular ease, and in case certain of the parts become worn and need replacement for any reason, the worn or otherwise damaged parts may be removed without it being necessary to dismantle remaining portions of the machine.

The system herein described is particularly effective in that it provides an adjusting device embodied in the differential mechanism which, although rotating in synchronism with the operating parts, is not subject to a load during normal operation of the machine. This is effected by employment of the worm wheel 111, 54, etc., as the case may be, which blocks the return of power through the differential. This construction promotes minimum wear of the differential parts, use of lighter weight differential parts, a decrease in the power necessary to turn the manual controls and the ability, because of minimization of wear, to hold a closer register.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent structures.

The invention having been herein described, what is claimed and sought to be secured by Letters Patent is:

1. In a continuous printing machine a frame, an impression roll rotatably mounted on the frame, plate cylinders rotatably mounted on the frame in parallel relationship with the impression roll, a drive shaft for the impression roll and plate cylinders, said impression roll comprising an impression cylinder having a positive drive connection to the drive shaft and a portion thereof in rotationally variable contact therewith, one of said plate cylinders having a positive drive connection to the drive shaft, a rotatably variable connection between the other plate cylinder and the impression cylinder, said variable connection comprising said portion and a change speed mechanism.

2. In a continuous printing machine a frame, an impression roll rotatably mounted on the frame, plate cylinders rotatably mounted on the frame in parallel relationship with the impression roll, a drive shaft adapted to drive said impression roll and plate cylinders, said impression roll comprising an impression cylinder having a fixed gear connection to the drive shaft and a portion thereof in frictional driving relationship with the impression cylinder and adapted to be rotated relative thereto, one of said plate cylinders having a positive drive relationship with the impression cylinder, a rotatably variable connection between the other plate cylinder and the impression cylinder, said variable connection comprising said portion and a differential mechanism, the differential mechanism comprising a housing rotatably mounted on the frame, an input shaft on the housing positively driven from the drive shaft, an output shaft on the housing, differential gears between said input and said output shafts, said output shaft having a positive drive connection with said portion, a positive drive connection between said portion and said other plate cylinder, and means for adjustably rotating said housing whereby to change the rotational relationship between the plate cylinders.

3. In a continuous printing machine a frame,

an impression roll rotatably mounted on the frame, plate cylinders rotatably mounted on the frame in parallel relationship with the impression roll, ink rollers for said plate cylinders and a hollow countershaft adapted to drive said impression roll, said impression roll comprising an impression cylinder having a fixed gear connection to the countershaft and an internal-external geared head in frictional driving contact with the impression cylinder and adapted to be rotated relative thereto, one of said plate cylinders having a tangential contact with the impression cylinder and a positive drive connection to the countershaft, the other plate cylinder having a rotatably variable relationship with the first plate cylinder and having a rotating connection with said impression roll including said geared head and a differential mechanism, the differential mechanism comprising a housing rotatably mounted on the frame, an input shaft on the housing positively driven from the countershaft, an output shaft on the housing, differential gears between said input and said output shafts, said output shaft having a positive drive connection with said geared head, a positive drive connection between the geared head and said other plate cylinder, and means for adjustably rotating said housing whereby to change the rotational relationship between said other plate cylinder and jointly said impression cylinder and the first plate cylinder.

4. In a continuous printing machine a frame, a plurality of impression rolls rotatably mounted on the frame, a plurality of plate cylinders for each impression roll rotatably mounted on the frame, and a drive shaft member adapted to drive said impression rolls, the impression rolls comprising impression cylinders and frictionally engaged rotating portions, said drive shaft member having positive and impositive drive connections to the impression cylinders, the positive drive connection being to one only of said impression cylinders, said impositive drive including an adjustable drive link comprising a rotating drum having a frictionally engaged rotating portion, a positive drive connection between each said impression roll rotating portion and one of said plate cylinders, another of said plate cylinders having a positive drive connection with one of said impression cylinders and the last remaining plate cylinder having a positive drive connection with the drive shaft member, and means for varying the rotational relationship between the plate cylinders comprising a variable speed device in each impositive drive connection.

5. In a continuous printing machine a frame, a pair of impression rolls rotatably mounted on the frame, a pair of plate cylinders for each impression roll rotatably mounted on the frame, and a drive shaft member adapted to drive said impression rolls, the impression rolls comprising each an impression cylinder and an auxiliary portion having a friction drive connection therewith, said drive shaft member having a positive drive connection to one impression cylinder and an adjustable drive connection to another impression cylinder, said last drive connection including a drum having an auxiliary portion in driving engagement with said last impression cylinder, a positive gear connection between each said impression roll auxiliary portion and one of said plate cylinders, another of said plate cylinders having a positive drive connection with one of said impression cylinders, and the last remaining plate cylinder having a positive drive connection with the drive shaft member, and means for

varying the rotational relationship between the plate cylinders comprising an adjustably variable speed device between the drive shaft member and each said auxiliary portion.

6. In a continuous printing machine a frame, a pair of impression rolls rotatably mounted on the frame, a pair of plate cylinders for each impression roll rotatably mounted on the frame, inking rolls for said plate cylinders and a drive shaft member adapted to drive said impression rolls, the impression rolls comprising each an impression cylinder, an internal-external geared head at one end of the impression cylinder having a friction drive connection therewith and a fixed gear at the other end of the impression cylinder, said drive shaft member having a positive gear connection to one impression cylinder, an impositive gear connection to a second impression cylinder including a rotating drum concentric with said drive shaft member, said drum having an internal-external gear in driving engagement with said impositively connected impression cylinder, a positive gear connection between each said geared head and one of said plate cylinders, another of said plate cylinders remaining having a positive drive connection with the drive shaft member and being in fixed rotational adjustment with one of said impression cylinders, and the last cylinder remaining having a positive drive connection with the other of said impression cylinders, and means for varying the rotational relationship between each geared head connected plate cylinder and said impositively connected impression cylinder respectively to the drive shaft connected plate cylinder comprising a differential gear connection between the drive shaft member and respectively said geared head connected plate cylinders and said impositively connected impression cylinder, said differential gear connection including a rotationally mounted housing, and means for rotating said housing whereby to adjust the register of said plate cylinders with relation to each other.

7. In a continuous printing machine a frame, a pair of impression rolls rotatably mounted on the frame, a plate cylinder for each impression roll in tangential contact therewith, and a drive shaft for rotating said impression rolls, a positive drive connection between one of said impression rolls and the drive shaft, positive drive connections between the plate cylinders and the respective impression rolls, and means adapted to vary the rotational relationship between said plate cylinders whereby to shift the register of plate cylinder impressions on print paper passing over said impression rolls, said means comprising a manually adjustable variable speed mechanism between the drive shaft and the other of said impression rolls, said mechanism comprising a housing mounted on the frame, manually adjustable means connected to said housing, an input shaft in the housing positively driven from the drive shaft and an output shaft, a drum housing, a friction head thereon, a bevel gear train in the drum housing in rotatable contact with said friction head, and a positive drive connection between said friction head and the other of said impression rolls.

8. In a continuous printing machine a frame, a pair of impression rolls rotatably mounted on the frame, a plate cylinder for each impression roll in tangential contact therewith, and a drive shaft for rotating said impression rolls, a positive drive connection between one of said impression rolls and the drive shaft, and means adapted

to vary the rotational relationship between said impression rolls whereby to shift the register of plate cylinder impressions on print paper passing over said impression rolls comprising a differential mechanism between the drive shaft and the other of said impression rolls, said differential mechanism comprising a housing rotatably mounted on the frame, manually adjustable means for rotating said housing, an input shaft in the housing positively driven from the drive shaft, an output shaft and a concentric shaft within said drive shaft positively driven from said output shaft, an internal-external gear concentrically mounted on the drive shaft, a drum housing in frictional engagement therewith, a bevel and worm gear train mounted in the drum housing and in rotatable contact with said internal-external gear, and a positive gear connection between said internal-external gear and the other of said impression rolls.

9. A mechanism for adjusting the relative rotation of parts of a composite roll, the parts of which include a cylindrical member and another member comprising a hollow head in rotatable frictional engagement with the first member, a frame to support the mechanism, means adapted to hold said members in frictional engagement, a drive shaft, a positive drive connection between the drive shaft and one of said members, and a variable speed mechanism between the drive shaft and the other of said members, said mechanism including a retainer rotatably mounted on the frame, rotational means therein having an input end and an output end, and a positive drive connection between the input end of the rotational means and the member comprising said hollow head.

10. A mechanism for adjusting the register of plate cylinders bearing insignia intended to cooperate in the production of a composite pattern comprising a frame, an impression roll having a cylindrical impression surface and a head in rotatable frictional engagement therewith, means adapted to hold said head in frictional engagement with the impression cylinder, a pair of plate cylinders in parallel tangential contact with the impression roll, a drive shaft and a variable speed mechanism, said mechanism including a retainer rotatably mounted on the frame adapted

to house the remaining portions of said mechanism, an input shaft positively driven by said drive shaft, an output shaft, a positive drive connection between the output shaft and said head, a positive drive connection between the head and one of said plate cylinders, a positive drive connection between the drive shaft and the other of said pair of plate cylinders, and manually actuated means adapted to adjust the rotational position of the retainer.

10. 11. A mechanism for adjusting the register of plate cylinders bearing insignia intended to cooperate in the production of a composite pattern comprising a frame, an impression roll having a cylindrical impression surface and a head in rotatable frictional engagement therewith, means adapted to hold said head in frictional engagement with the impression cylinder, a drive shaft and a variable speed mechanism, said mechanism including a rotating means rotatably mounted on the frame, a positive drive connection between the rotating means and said head including bevel and worm gears in the impression cylinder, a pinion rotatably mounted in an eccentric location at the end of the impression cylinder and located within said head, an internal gear in the head meshing with the pinion, and a positive drive connection between the head and one of said plate cylinders.
